UNITED STATES PATENT OFFICE.

FREDERICK A. ANTON, OF TOPEKA, KANSAS.

ADJUSTABLE AWNING.

Application filed September 14, 1925. Serial No. 56,200.

This invention relates to window awnings of that class in which the awning fabric is wound or unwound upon a roller, and adapted in the latter condition, to provide an upper right or straight portion and an inclined or visor portion, and is designed as an improvement over my copending application for patent filed September 17, 1923, Serial No. 663,142, in which the visor is adjustable both as to its own extent or area and its position intermediate the ends of the window.

With the type of construction shown in said copending case, it has been found the tension of certain springs was of extreme importance if satisfactory operation of the awning was to be secured, as with each change in proportion of parts or in weights of material, it was necessary to utilize a spring of a different tension. When the springs were properly proportioned as regards the other parts of the awning, the awning would operate with entire satisfaction. However, when the springs exerted too great a pull, the visor would be formed immediately the tension of the pull rope was relaxed, and when the spring tension was too light, the visor would immediately collapse upon exerting a pull on the pull rope. These faults of operation were, of course, objectionable as it necessitated trial fittings of different springs upon each installation of an awning, if an adjustable visor was desired.

With the type of construction illustrated in this application, however, the tension of the springs can vary within relatively wide limits, the only requirement being that the force exerted by said springs shall be stronger than ordinary gusts of wind tending to collapse the awning.

With the objects of producing an awning of the type last mentioned, the invention consists in certain novel and useful features of construction and organization of parts as hereinafter described and claimed; and in order that it may be fully understood, reference is to be had to the accompanying drawings, in which:

Figure 1 is a face view of one side of an awning embodying the invention, as it will appear in collapsed or rolled position.

Figure 2 is a side view of the same, and illustrates the open position of the awning in dotted lines at the bottom of certain slide or guide ways.

Figure 3 is a perspective view of the awning as it appears in dotted lines in Figure 2.

Figure 4 is a reduced side view of the awning as it will appear with a partial visor at a point intermediate the length of the vertical guides.

Figure 5 is an enlarged detail view of the construction of the visor-forming guide bar and friction catch device.

Figure 6 is a section on the line VI—VI of Figure 5.

In the said drawing, where like reference characters identify corresponding parts in all of the figures, 1 indicates a window opening, and 2 one of a pair of brackets secured to the frame of the window and provided with conventional or other suitable arms 3 for the operative support of a roller 4 on which is wound the fabric of the awning 5.

Secured to the lower end of the bracket 2, it being understood that the other side of the window will be provided with duplicate equipment, is an arm or flange 6 to which is secured the upper end of a slightly outwardly inclining guide rod 7, having its lower end fixed in a bracket 8 secured to the window frame adjacent its lower corner or at any other desired limiting point for the extension of the awning.

A slide 9 is mounted on the rod 7 and said slide at its lower end is preferably provided with an anti-friction roller 10 slipped into position in a curved passageway 11 and bearing against the rod 7. The slide 9 is also formed with a pair of ears 12 between which is pivoted one end of a relatively long bodied U-shaped roller guide 13, formed with a socket at its outer end for engagement with one of the side arms 14 of the visor frame 15.

Mounted on the guide 7 is a slide 21, having an outwardly-projecting bifurcated lug 22. A sliding or rolling brace member 23 is pivotally secured adjacent its upper end in the lug 22 of the slide 21, and said brace member is equipped at its lower end with an anti-friction roller 24 riding on the guide 13, although it will be understood that any other method of providing a relatively sliding connection between the described members may be employed.

The continued engagement of the roller 24 with the guide 13 and consequently a continued downward pressure of the former on the latter is insured by means of a retractile spring 25 connected at one end to a suit-

able hook 26 on the brace 23, and connected at its other end to a suitable hook 27 formed on the slide 9.

The upper end and inner face of the brace 23 is formed with a conical recess 28 and an alined hole or passageway for reception of a headed bolt 29. The cross or bar member effecting the formation of the visor, comprises a hollow tube 30 in the end of which 10 is forcibly driven to secure rigidity, an end member 31 having its extremity formed with a conical head 32 for reception within the socket 28 of the brace 23, and said member 31 is also formed with a side channel or key- 15 hole slot 33 for reception of the headed bolt 29, whereby the brace member may be securely fastened in position and still lend itself to ready dismantlement.

The awning roller 4 is equipped at one of 20 its ends with a suitable spool or pulley 34, in which is wound the pull rope 35, extending downwardly through a guide loop 36 and being secured at its lower end to any suitable type of fastening device 37.

25 The operation of the awning is substantially as follows: With the awning and its operative parts in the folded position shown in Figures 1 and 2, the weight of the movable part of the structure is supported by the pull 30 rope 36, and the springs 25 are under a slight tension tending to effect the formation of the visor, but this tendency is overcome by the preponderance of force exerted by the fabric on the U-frame 15 holding 35 the same collapsed as imposed by the weight of the structure on said fabric. The pull rope is now gradually relaxed and the structure in collapsed position, descends the guides 7, until the bottom of the slides 9 40 contact with the supporting brackets 8. When this occurs, the weight of the structure is transferred from the fabric 5 to the brackets 8, and the force of the tensioned springs 25 applying downward pressure 45 through the roller 24 of the brace 23 eccentrically of the pivotal point of the extended U-shaped guides 13, effects the outward swinging of the U-frame 15, until the full visor is formed and the braces 23 have assumed the position shown in dotted lines, 50 Figure 2, by riding outwardly on the guides 13. During this unfolding operation of the visor, the tension on the springs will be slightly decreased as the plane of the rollers 55 24 in their final position on the guides 13, relative to the pivotal points of the latter, is slightly lower than that of the plane of the rollers when the visor is in folded position, as clearly illustrated in dotted and full lines 60 respectively in Figure 2.

The tension of the springs with the visor in lowered position, however, is sufficient to maintain the visor and fabric taut and to counteract any tendency of puffs of wind to 65 effect the collapse of said visor. It is also

to be clearly understood at this point that the force exerted by the braces on the U-frame of the visor, is greater than the force tending to collapse the visor when the pull rope is rolled to effect the raising of the awning, that is with the awning in its open position shown in Figure 1, when force on the straight portion of the fabric 5 is exerted, tending to collapse the visor, said force is equal to the entire weight of the structure, but is split up in a series of forces through the effect of the relatively large friction between the bar 30 and the fabric. Due to the resultant force from the outward and upward pressure of the fabric on the cross bar 30, the weight of the braces 23 and slides 21 and 9, is partially removed from the visor portion of the fabric. The arms 14 of the U-frame 15 and the guides 13 are therefore 70 75 80 85 90 95 100 acted upon as if they formed a single lever with a fulcrum at the points of engagement of the rollers 24 with the said guides 13, the pull of the fabric being exerted at one side of the fulcrum through the cross bar 15 of the U-frame, and the pull of the springs 23 being exerted on the other end of the lever through its connection to the slides 9. With this explanation of the operation, which is believed to be substantially correct, it will be evident that as long as the springs 23 exert a greater force at one end than the pull of the fabric at the other end, it will be impossible for the visor to collapse, until the structure as a whole has been elevated to the tops of the guides 7, and the slides 21 meet with an obstruction.

When this occurs, the operator continues to pull on the pull rope and overcomes the force of the springs 23 and starts the collapse of the visor, the springs 23 being tensioned at first until the guides 13 swing from a position below the horizontal, as shown in dotted lines Figure 2, to the horizontal, from which point the tension on the springs commences to decrease. As soon as the guides reach an inclined position, slightly greater in pitch than that shown in Figure 4, a tripping action occurs, and the rollers and braces rapidly travel downward on the guides to the full-line position shown in Figure 2, the visor rapidly collapsing and the entire structure sliding downward on the guides 7 a length equal to the suddenly collapsed portion of the visor. The operator then continues to roll the fabric 5 on the roller 4 until completely wound upon the roller.

If the operator now desires to form a partial visor at the bottom of the guides 7, he lowers the structure as described, and then merely slackens the pull rope until a visor of the desired area has been secured. The rollers of the braces 23, when the visor is formed in this fashion, will remain at the inner ends of the guides 13, and it will be 125 130 135

impossible to adjust the partial visor so formed to varying heights of the window, as the springs 25 do not have enough leverage on the braces to overcome the force tending to collapse the visor when it is attempted to elevate the entire structure.

However, if the operator desires to form a partial visor at a particular point intermediate the top and bottom of the window, 10 he will permit the full visor to be formed at the bottom thereof, the braces 23 thus rolling outwardly on the guides 13 and giving the spring 25 a preponderancy of leverage over the visor. He will then elevate the entire visor, and will permit the slides 21 to contact with the brackets 6 as if he intended to entirely collapse the mechanism. He will continue to pull on the rope and roll up the fabric 5 thus decreasing the area of the visor, 20 until it has attained any size between full extension and substantially the position shown in Figure 4, which is just short of the tripping point of the braces. The visor thus formed may now be lowered to any desired point, as the braces 23 are at the outer ends of the guides 13 and the force of spring 25 thus preponderates over the force tending to collapse the visor.

From the above description of the operation 30 of the invention, it will be apparent that the proper operation thereof is dependent to some extent on the creation of a resultant force through the friction between the fabric 5 and the cross bar 30. It has been thought desirable, therefore, in order to absolutely insure the proper operation 35 of the awning under all weather conditions, such as moisture, windy weather and the like, to provide friction or catch means on the cross bar for engagement with the awning at their point of contact when the visor is fully extended. As one means of carrying out this frictional engagement, the fabric is provided near its side edges 40 (one edge only being illustrated) with grommets 38 for detachable reception of studs 39 formed at the ends of the cross bar 31 (see Figure 6). With the parts so interlocked, it will be evident that the accidental 45 collapsing of the visor when it is attempted to elevate the entire structure is positively guarded against.

It is also desirable in this connection to point out that the fabric is preferably 50 rolled on the roller 4 in the manner illustrated, so that by the time the bar 31 is elevated, the increase in diameter of the roller due to the rolled fabric, will throw the fabric to the dotted line position in Figure 6, 55 and thus get it into proper position for the ready release or disengagement of the grommets 38 from the studs 39.

It is believed the construction and operation 60 of the invention has been sufficiently set forth to obviate further recapitulation, and

it is to be understood, that while I have described and claimed the preferred embodiment of the invention, I reserve the right to make all claims properly falling within the spirit and scope of the appended claims. 70

I claim:—

1. A window awning, comprising a roller, a fabric attached at its upper end to said roller, a vertically movable and pivoted U-frame attached to the lower end of the fabric, a visor-forming bar, and yielding means having a shifting connection with the U-frame and applying force tending to oppose the pull of the fabric. 75

2. A window awning, comprising a roller, a fabric attached at its upper end to said roller, a vertically movable and pivoted U-frame attached to the lower end of the fabric, a visor-forming bar, and yielding means having a shifting connection with the U-frame whereby the force applied by said means is substantially the same when the U-frame is vertical or horizontal. 85

3. A window awning, comprising a roller, a fabric attached at its upper end to said roller, a vertically movable and pivoted U-frame attached to the lower end of the fabric, a visor-forming bar, and yielding means having an inwardly and outwardly sliding connection with the U-frame to decrease or increase its leverage on said U-frame. 90

4. A window awning, comprising a roller, a fabric attached at its upper end to said roller, a vertically movable and pivoted U-frame attached to the lower end of the fabric, a visor-forming bar, cooperating friction means carried by said bar and the fabric at their normal engagement point, and yielding means applying force on said U-frame opposing the pull of the fabric. 100

5. The combination of a cross-bar and supporting arms, comprising interengaging heads and sockets, the latter being provided with a passageway, a headed bolt in said passageway, and the heads being formed with a transverse slot for the reception of said headed bolts. 110

6. A window awning comprising a roller, a pair of vertical guide bars, a U-frame having its ends slidably mounted on and pivoted to said guide bars, a visor-forming bar slidably mounted on said guide bars, connections between said U-frame and visor-bar and having shifting attachment to the former, and a fabric attached at its opposite ends to the roller and U-frame respectively and in engagement with said visor-bar. 115

7. A window awning comprising a roller, a U-frame pivoted at its ends, a visor-bar secured above said U-frame, connections between said U-frame and visor-bar and having shifting attachment to the former, and a fabric attached at its opposite ends to the 120 125 130

roller and **U**-frame respectively and in engagement with said visor-bar.

8. A window awning comprising a roller, a **U**-frame pivoted at its ends, a visor-bar secured above said **U**-frame, connections between said **U**-frame and visor-bar and having shifting attachment to the former, yielding means applying downward force on said

connections, and a fabric attached at its opposite ends to the roller and **U**-frame respectively and in engagement with the visor-bar. 10

In witness whereof I hereunto affix my signature.

FREDERICK A. ANTON.
